AUTOMATIC DOOR LOCKING DEVICE

Frank T. Pivero, San Diego, Calif.

Application October 20, 1947, Serial No. 730,904

3 Claims. (Cl. 292—33)

1

My invention relates to an automatic door locking device, more particularly for use in connection with motor vehicles for preventing automobile doors or the like from becoming open when in transit and the objects of my invention are:

First, to provide an automatic door locking device of this class which is particularly improved over my former application for Letters Patent for automatic door locking device for automobiles, Ser. No. 773,167, filed September 10, 1947.

Second to provide a device of this class having novel valve means for controlling the vacuumatic operation of said device which permits the operator to simply press a button in the operator's compartment of the motor vehicle for releasing the automobile doors so that they may be opened in the conventional manner.

Third, to provide a device of this class having a novel door striker plate and a reinforcing plate provided with elongated openings therein surrounding the plungers of the locking device, whereby the door may be opened to the second step of the conventional latch without causing drag of the striker plate in its surrounding relationship with the locking plunger of said device.

Fourth, to provide a device of this class in which a solenoid actuated plunger is operated by a key switch permitting automatic locking of automobile doors when the operator thereof leaves the automobile so that said electrical key operated switch is employed in order to enter the automobile, whereby automobile doors may be automatically locked regardless of the negligence on the part of said operator who occasionally forgets to lock the doors.

Fifth, to provide a device of this class which is very simple and easy to install in connection with conventional automobile doors and door jambs.

Sixth, to provide a device of this class which is very positive and simple of operation.

Seventh, to provide a device of this class which is automatically in operation when the engine of the automobile to which it is attached is running.

Eighth, to provide a device of this class which is very simple and economical of construction, efficient in operation and which will not readily deteriorate or get out of order.

With these and other objects in view as will appear hereinafter, my invention consists of certain novel features of construction, combination and arrangement of parts and portions and a certain modification as will be hereinafter de-

scribed in detail and particularly set forth in the appended claims, reference being had to the accompanying drawings and to the characters of reference thereon forming a part of this application in which:

Fig. 1 is a fragmentary side elevational view of an automobile door and door jamb showing my automatic door locking device in connection therewith; Fig. 2 is an enlarged fragmentary sectional view taken from the line 2—2 of Fig. 1; Fig. 3 is a fragmentary sectional view taken from the line 3—3 of Fig. 2; Fig. 4 is a fragmentary sectional view taken from the line 4—4 of Fig. 3; Fig. 5 is a longitudinal sectional view of the operating valve used in connection with my automatic door locking device and forming a part thereof; Fig. 6 is a diagrammatic view of the operating mechanism of my automatic door locking device; Fig. 7 is a side elevational view of an automobile door and jamb shown fragmentarily and illustrating in connection therewith a modified form of my automatic door locking device; Fig. 8 is an enlarged fragmentary sectional view taken from the line 8—8 of Fig. 7; Fig. 9 is a fragmentary sectional view taken from the line 9—9 of Fig. 8; Fig. 10 is an enlarged fragmentary sectional view taken from the line 10—10 of Fig. 7 showing parts in elevation to facilitate the illustration; Fig. 11 is a rear view of the structure as shown in Fig. 10 of the drawings taken from the line 11—11 of Fig. 10 and Fig. 12 is a diagrammatic view of the wiring of the modified structure as shown in Figs. 7 to 11 inclusive.

Similar characters of reference refer to similar parts and portions throughout the several views of the drawings.

Door 1, door jamb 2, striker plate 3 and reinforcing plate 4, cylinder 5, plunger 6, spring 7, cylinder cap 8, valve 9, valve casing 10, valve plunger 11, and spring 12 constitute the principal parts and portions of my automatic door locking device as shown in Figs. 1 to 6 inclusive of the drawings.

The door 1 and door jamb 2 as shown in Fig. 1 of the drawings are conventional in the structure of automobiles now in use and the striker plate 3, reinforcing plate 4 are connected to the outer and inner sides respectively of the wall 1a of the door 1 at its edge, as shown best in Fig. 2 of the drawings. It will be here noted that these plates 3 and 4 provide the plunger-engaging plate means of my automatic door locking device. The striker plate 3, reinforcing plate 4 are provided with elongated openings 3a and 4a coinciding with each

other and communicating with an opening $1b$ in the wall $1a$ of the door 1 and coinciding therewith. It will be noted that the openings $3a$ and $4a$ coinciding with the opening $1b$ are all elongated horizontally and arranged to permit play of said openings $3a$, $4a$ and $1b$ about the plunger 6 at its end portion $6a$ within the limits of travel permitted by the conventional step latch in connection with automobile doors, whereby opening of the door 1 to the second step of the latch leaves the plunger bolt portion $6a$ in untouched position within the openings $3a$ and $4a$ of the plates 3 and 4 due to the elongation of said openings $3a$ and $4a$. The screws $3b$ extending through the plate 3 are threaded in the reinforcing plate 4 at the inner side of the wall $1a$ at the edge of the door 1 for holding said plate in a predetermined position. The cylinder 5 , plunger 6 , spring 7 and cylinder cap 8 are similar in structure to my prior application hereinbefore set forth. Communicating with the cylinder 5 is a vacuum tube $5a$ which is connected to the valve casing 10 as shown best in Figs. 5 and 6 of the drawings. Connected to the inlet of the valve 10 is a tube $10a$ which is connected to the automobile intake manifold A , as shown in Fig. 6 of the drawings. The valve casing 10 is a hollow, cylindrical casing having a bore $10b$ therein, in which the plunger 11 is reciprocally mounted. This plunger 11 is provided with a reduced stem $11a$ on the outer end of which is positioned a thumb piece $11b$. Surrounding the stem $11a$ is an O ring $11c$, and in the opposite end of the plunger 11 is the spring 12 which tends to force the plunger into a position wherein the thumb piece $11b$ occupies the dash line position as shown in Fig. 5 of the drawings, whereby the tubes $10a$ and $5a$ communicate directly for evacuating the cylinders 5 and forcing the plunger 6 outwardly into the position as shown in Fig. 2 of the drawings. In the cylinder 10 is a vent opening $10c$ arranged to communicate with the tube $5a$ when the plunger 11 is in the solid line position as shown in Fig. 5 of the drawings. The valve 9 is connected with one of the cylinders 5 , controlling one door of the automobile as shown fragmentarily in Fig. 1 of the drawings, so that the automobile engine may be left running while the operator leaves the car and closes the doors. The valve 9 is provided with a plunger $9a$ operated at the outer side of the door jamb 2 so that the operator may open one of the doors of the automobile from the outside when the engine is running and forcing the plunger 6 outwardly into the solid line position as shown in Fig. 2 of the drawings. The valve 9 is similar to the valve 10 or may be a barrel valve if desired for simply venting the cylinder 5 at one of the doors as shown in Fig. 6 of the drawings.

The operation of my automatic door locking device is substantially as follows:

When the engine in connection with the intake manifold A as shown in Fig. 6 of the drawings is operating, all of the plungers 6 in the cylinders 5 are forced outwardly against compression of the springs 7 engaging said plungers 6 . The door 1 , as shown in Fig. 2 of the drawings, may be opened slightly in the direction of the arrow B in Fig. 2 of the drawings, wherein the elongated openings $3a$ and $4a$ in the plates 3 and 4 pass over the plunger bolt portion $6a$ until the door 1 reaches the second step of the conventional latch, wherein clearance of the bolt portion $6a$ is still maintained within the elongated openings $3a$ and $4a$ of the plates 3 and 4 , 75

permitting smooth retraction of the plunger 6 by the spring 7 when the vacuum in the intake manifold A ceases due to discontinued operation of the motor in connection with said manifold A . This clearance of the openings $3a$ and $4a$ of the plates 3 and 4 with the bolt $6a$ of the plunger 6 is also necessary when the thumb piece $11b$ of the plunger 11 is depressed, forcing the plunger 11 into the solid line position as shown in Fig. 5 of the drawings for venting one of the cylinders 5 through the hole $10c$ and tube $5a$ respectively. The valve 10 is normally placed on the instrument panel of the operator's compartment of the vehicle so that all of the doors 10 may be released by the plungers 6 and opened in the conventional manner as desired. The valve 9 is only used to gain entrance to the automobile from the outside thereof when the engine of the automobile is running, creating vacuum in the intake manifold A , all as hereinbefore described.

In the modification as shown in Figs. 7 to 12 inclusive of the drawings, the parts are designated as follows:

The door 13 , door jamb 14 , striker plate 15 , reinforcing plate 16 , cylinder 17 , plunger 18 , spring 19 , switches 20 and 21 , solenoid 22 and the cap and stop member 23 . The door 13 , door jamb 14 and plate 15 and reinforcing plate 16 are all similar to the structure hereinbefore described in connection with Figs. 1 to 6 inclusive of the drawings. The cylinder 17 houses the solenoid 22 which is electrically operative in connection with the plunger 18 having a stop flange $18a$ arranged to abut the end of the cylindrical portion $22a$ of the cap and stop member 23 which closes the end of the cylinder 17 . The spring 19 tends to force the plunger 18 outwardly in a similar manner to the structure of my prior application for Letters Patent as hereinbefore set forth.

The switch 20 is secured in the outer side wall $14a$ of the door jamb 14 and is provided with a tumbler lock portion $20a$ having a stationary contact portion $20b$ mounted thereon, engageable with the movable contact portion $20c$ operated on the axis pin $20d$ of the tumbler lock portion $20a$ which is operated by a key at the entrance side $20e$, all as shown best in Figs. 10 and 11 of the drawings. This switch 20 being operated by a key is employed for the purpose of gaining entrance to the automobile from the outside thereof when all of the springs 18 are forcing the plungers 18 into the plates 15 and 16 in the door 13 all as shown best in Figs. 8, 10 and 11 of the drawings.

The switches 20 and 21 are connected to an electrical circuit, which is shown in Fig. 12, this circuit including a battery, which may be the storage battery of an automobile and may be suitably grounded to the frame of the automobile. The switches are also suitably connected through this circuit to the solenoids 22 , enclosed in the various cylinders 17 , as shown in Fig. 12, these solenoids also being suitably grounded to the frame of the automobile.

In the operation of the modified form of my automatic door locking device as shown in Figs. 7 to 12 inclusive of the drawings, I have provided a manually operated switch 21 which is arranged to momentarily retract all of the plungers 18 by means of the solenoids 22 when it is desired to open any of the automobile doors 13 in the conventional manner. This switch 21 is accessible at the inner side of the automobile body. The switch 20 , as hereinbefore described and disclosed in Figs. 10 and 11, is used to gain entrance

to the automobile body from the outside thereof.

Though I have shown and described a particular construction, combination and arrangement of parts and portions and a certain modification, I do not wish to be limited to this particular construction, combination and arrangement nor to the modification, but desire to include in the scope of my invention, the construction, combination and arrangement substantially as set forth in the appended claims.

Having thus described my invention, what I claim as new and desire to secure by Letters Patent is:

1. In an automatic door locking device of the class described, the combination of a plurality of vacuum cylinders, plungers in said cylinders, plunger-engaging plate means adapted to be connected with doors, said plate means having elongated openings therein adapted to surround said plungers permitting substantial opening of the door without retraction of said plungers.

2. In an automatic door locking device of the class described, the combination of a plurality of vacuum cylinders, plungers in said cylinders, plunger-engaging plate means adapted to be connected with doors, said plate means having elongated openings therein adapted to surround said plungers permitting substantial opening of the door without retraction of said plungers, springs

arranged to retract said plungers, valve means communicating with said cylinders arranged to vent the same and permit said springs to retract said plungers.

3. In an automatic door locking device of the class described, the combination of a reciprocal plunger having a stationary axis, plunger-engaging plate means connected to a door and having a plunger receiving portion extending laterally of the door a greater distance than the diameter of said plunger, and thereby permitting a certain movement of said plunger-engaging plate means laterally of said plunger after said plunger is received by said plunger-engaging plate means.

FRANK T. PIVERO.
